PAIR OF SWIM WORK-OUT GOGGLES

Aubrey Burer, 1542 La Playa Ave.,
San Diego, Calif. 92109

Filed Feb. 18, 1972, Ser. No. 227,696

Term of patent 14 years

Int. Cl. D16—06

U.S. Cl. D2—234

Fig. 3

FIG. 4

FIG. 5.

FIG. 1 is a perspective view of a pair of swim work-out goggles embodying my new design;

FIG. 2 is a side elevation of the same;

FIG. 3 is a front elevation;

FIG. 4 is a bottom view of the goggles; and

FIG. 5 is a rear elevational view thereof, the strap and buckle being omitted for purposes of disclosure.

I claim:

The ornamental design for a pair of swim work-out goggles, as shown.
